[57] CLAIM

The ornamental design for a housing for electronic audio communication device, as shown and described.

DESCRIPTION

FIG. 1 is a front elevational view of a housing for electronic audio communication device, showing our new design;

FIG. 2 is a side elevational view thereof, the opposite side being a mirror image;

FIG. 3 is a rear elevational view thereof;

FIG. 4 is a bottom plan view thereof; and,

FIG. 5 is a top view thereof, taken along the line 5—5 of FIG. 2.
